UNITED STATES PATENT OFFICE.

WENDELL WRIGHT, OF PHœNICIA, NEW YORK.

IMPROVEMENT IN FOLDING COT-BEDSTEADS.

Specification forming part of Letters Patent No. **150,993**, dated May 19, 1874; application filed August 4, 1873.

To all whom it may concern:

Be it known that I, WENDELL WRIGHT, of Phœnicia, in the county of Ulster and State of New York, have invented a new and useful Improvement in Folding Cot-Bedsteads, of which the following is a specification:

The invention will first be described, and then pointed out in the claim.

Figure 1 represents a vertical longitudinal section of the bedstead, taken on the line $x x$ of Fig. 2. Fig. 2 is a plan view.

Similar letters of reference indicate corresponding parts.

A A are the side rails; B, the head, and C the foot board. D D are cross-rails, which support the slats E. F represents the legs. The legs at each end are connected by a transverse rail, and are pivoted to the side rails at the points G, so that they will readily fold back against the inner sides of the side rails. When the bedstead is in use the legs stand bracing, and are supported by the head and foot boards, the end pieces of which have pro-

jections H, which enter mortises in the legs, as seen in Fig. 1. The legs may be supported by the cross-rails D D.

In this example of my invention I pivot the foot-board at the point I, so that it will fold down between the side rails. The head may also be pivoted so as to fold in a similar manner. The legs may bear against the cross-rails; but by means of the projection H on the head and foot boards the legs are more perfectly supported than they would be by the rails D D.

Having thus described my invention, I claim as new and desire to secure by Letters Patent—

The pivoted head and foot boards B C, having projections H, combined with mortised and pivoted legs, in the manner and for the purpose described.

WENDELL WRIGHT.
